UNITED STATES PATENT OFFICE.

WILLIAM H. HUBBARD, JR., OF SALIDA, COLORADO, ASSIGNOR TO THE OHIO & COLORADO SMELTING & REFINING CO., OF DENVER, COLORADO, A CORPORATION OF COLORADO.

COOLING ORE.

1,149,264.

Specification of Letters Patent. Patented Aug. 10, 1915.

Application filed November 30, 1912. Serial No. 734,315.

To all whom it may concern:

Be it known that I, WILLIAM H. HUBBARD, Jr., a citizen of the United States, residing at Salida, county of Chaffee, State 5 of Colorado, have invented certain new and useful Improvements in Cooling Ore; and I do hereby declare the following to be a full, clear, and exact description of the invention, such as will enable others skilled 10 in the art to which it appertains to make and use the same.

The present invention relates to cooling ores or the like from metallurgical or other furnaces, such, for example, as the product 15 of a pre-roasting furnace of the Godfrey or analogous type, which is to be further treated on Dwight and Lloyd machines or the like.

The object of the invention is to effect the 20 cooling of the ore at the intermediate stage quickly and cheaply, at the same time avoiding the annoyance of dust and smoke and bringing the ore into good physical condition for handling easily and further roasting.

In accordance with the invention, the hot ore is distributed in a comparatively thin 25 layer on a flat table, or a series of tables and is rabbled during its movement between the places of charge and discharge to continually expose fresh surfaces of ore to a cooling medium or mediums. The cooling 30 tables for supporting the ore in this way may have a variety of forms; they 35 may be circular, linear or otherwise shaped, and may be arranged in tiers to form superposed tables, if desired. So, also, the rabbles for rabbling the ore may take various forms, and may have the various arrangements 40 relatively to the cooling tables. However, it is preferable that either the tables or the rabbles, or both, should be movable in such manner as to produce a relative movement between the two, and also 45 so as to produce a movement of the ore on the table in a path different from the line of movement of the table or the rabbles, and also extended in length so far as practicable. In the preferred embodiment of 50 the apparatus for carrying out the invention, the table is substantially circular, while the path of the ore on the table is along a substantially spiral line, this being effected either by rotating the table

and providing stationary rabbles, or by rotating the rabbles and providing a stationary table, so that in either case, the ore is periodically forced against rabbles to rabble it and to simultaneously shift it on the table progressively toward the discharge 55 outlet. In this way the ore is automatically discharged after being repeatedly rabbled to expose fresh surfaces to the cooling medium or mediums along an extended path across the table and yet within a compact 60 space of operation.

The cooling medium may be a current of gas, such as air, moved over and in contact with the ore on the table or through it, and of such volume and temperature as to produce 65 the necessary reduction in the temperature of the ore under the conditions prevailing. As an alternative method of cooling, heat from the ore may be transferred to a cooling medium, such as water, circulated 70 in contact with the under side of the table by conduction through the table, or liquid may be sprinkled on the ore to abstract the heat of vaporization of the liquid from the ore. Furthermore, all, or any two of these 75 cooling means may be used together to effect the desired reduction in temperature of the ore during its passage from the place of charge to the place of discharge.

In the accompanying drawings, illustrating 80 the preferred form and several modifications of apparatus suitable for carrying out my preferred method of cooling ore, Figure 1 represents an elevation, partly in section and partly broken away, of the arrangement 85 wherein the table is stationary, while the rabbles are rotatable; Fig. 2 is a diagram of the movement of the ore on the table in Fig. 1; Fig. 3 represents an elevation, partly in section, of an arrangement 90 wherein the table is rotatable, while the rabbles are stationary, and wherein the ore on the table is sprinkled with the cooling liquid; Fig. 4 is a diagram of the movement of the ore on the table of Fig. 3; Fig. 5 represents a central sectional elevation of an arrangement 95 having a rotatable table and stationary rabbles, wherein a cooling fluid is circulated interiorly of the table, while a liquid is sprinkled on the ore; Fig. 6 represents a top plan view of the apparatus 100 shown in Fig. 5; Fig. 7 represents an elevation, partly in section and partly broken

away, of an apparatus having two superposed tables; and Fig. 8 is a diagram of the movement of the ore on the lower table of Fig. 7.

Referring to Figs. 1 and 2 of the drawings, the columns 1 resting on a suitable foundation 2 support the hood 3 over the stationary circular table 4. A vertical shaft 5 mounted in suitable bearings 6 is driven by the gearing 7 and carries the arm 8 provided with the rabbles 9. The rabbles 9 are arranged along substantially a diametrical line across the circular table, and are each set at such an angle to this line that when the driving shaft 5 is rotated the ore on the table is carried along a substantially spiral path, indicated by the broken lines in Fig. 2. The hood 3 is provided with a stack 10 to conduct the dust and gases away from the apparatus. The charging ore conduit 11 may extend directly from a preheating furnace or from any other suitable place and charge the hot ore onto the table at a place near the outer periphery thereof. The discharge ore conduit 12 is fastened to the under side of the table around its discharge opening 13 and leads to any desired place, as a storage bin or a conveyor.

When the shaft 5 is rotated at the proper speed by the gearing 7 and the ore is being charged at the proper rate of feed onto the outer periphery of the stationary table 4 from the conduit 11 in Figs. 1 and 2, the rabbles 9 push the ore in a comparatively thin layer around the table and inwardly thereon in a spiral path and finally into the central opening 13, from whence it passes through the discharge conduit 12 into a place arranged to use, store or convey the ore. In this period during which the ore is moved from the charging conduit to the discharging conduit, the air is drawn from the outside over and in contact with the ore and into the stack 10, either by a natural draft brought about by the hot gases and heated air, or by a suitable fan. In either case, the air moves freely without substantial confinement by the apparatus at any point, while the volume of the cooling air is regulated in any suitable way to bring about the desired reduction of temperature of the ore in its movement on the table. The ore is caused to move along a substantially spiral path considerably longer than the distance between the conduits, so that an extended cooling operation is secured in a comparatively compact apparatus. Furthermore, the ore is repeatedly rabbled so that by continually exposing fresh surfaces thereof contact with the cooling air, the ore is progressively and efficiently cooled throughout its mass.

In Figs. 3 and 4, the circular table 19 is fastened to the driving shaft 5 and is rotatable therewith, while the rabbles 9 are sta-

tionary. Furthermore, the ore is charged onto the table near the center thereof, and is discharged from the outer periphery by the outermost rabbles 9^a into a conduit 12 located at the proper place to catch the ore falling from the table. In addition to the cooling effect of the current of air, water is sprinkled on the ore, preferably at the places indicated diagrammatically in Fig. 4, just behind the rabbles in the direction of rotation of the table where the ore has just been overturned. The sprinkling apparatus comprises a stationary pipe 20 closed at its ends and provided with a series of holes through which the water passes out into the freshly exposed ore. This pipe 20 is bent around the driving shaft 5 and is connected to a supply pipe 21 which communicates with a source of water supply.

In Figs. 3 and 4, the ore is moved around and outwardly upon the table in an extended path of substantially the form of a spiral and is repeatedly rabbled and is sprinkled by cooling the liquid to a degree sufficient to effect the desired reduction of temperature when combined with the additional cooling effect of the air current induced over the ore. In this way the heat of vaporization of the water is taken from the freshly exposed ore, while the direction of the current of air is against the movement of the ore so that the coolest air meets the coolest ore at the outer periphery of the table.

In Figs. 5 and 6, the table 4' is rotatable and the rabbles 9 are stationary, whereas the ore is charged onto the table near the center thereof and is discharged at the outer periphery into a suitable receptacle, such as the car indicated in outline in broken lines. In addition to the current of cooling air induced over the ore, and the stationary water sprinkling system, heat is also abstracted from the ore by water circulated in the hollow interior 30 of the table and provision is made for drawing air through the ore bed. The circulating cooling water is supplied from a pipe 31 communicating with a suitable source and with the hollow interior 32 of the driving shaft. Conduits 33 fixed in the hollow interior of the table communicate with the passage in the shaft and conduct the water near the outer periphery of the table, from whence the water passes back through the discharge pipes 34, when it reaches the required level, and out through the stationary pan 35 and outlet 36. In this way heat is conducted from the ore through the table to this circulating cooling water. The table is also provided with a plurality of radially arranged narrow inclosed passages 37 passing entirely through the table without permitting the leakage of water from the hollow interior of the table, for the purpose of passing air through the ore

on the table. The air currents, the sprinkling water, and the circulating cooling water are regulated in amount so as to effect in combination the desired reduction of temperature of the ore during its movement from the place of charge to the place of discharge.

The apparatus of Figs. 7 and 8 comprises a stationary upper table 4, as in Fig. 1, and a 10 rotatable lower table 41, as in Fig. 5, the upper set of rabbles, 9 being rotatable and the lower set being stationary. The ore is charged onto the outer periphery of the upper table and discharged from a point near 15 the center thereof to a point near the center of the lower table, and thence to the outer periphery of the lower table into the discharge conduit, so that the ore is moved through a substantially spiral path on each 20 of the tables. Currents of cooling air may be induced over or through the ore on each of the tables, and the ore on either or both tables may be additionally cooled by sprinkling with liquid from distributing pipes, 25 stationary or rotatable, as the case may require, or by the conduction of heat from the ore to a circulating fluid in the manner similar to that previously described for carrying out each of these features. The pipe 31 is 30 intended to supply water for cooling the ore on the lower table by conduction, as in Fig. 5, while the spray pipe 20 is intended to spray water on the freshly overturned ore on the lower table, as in Fig. 3. Furthermore, 35 the lower table is provided with inclosed passages, as in Figs. 5 and 6 for passing cooling air through the bed of ore.

Having thus described my invention, what I claim is:

40 1. In apparatus for cooling hot ore or the like, the combination with a flat circular cooling table for supporting the ore in a comparatively thin layer, means for charging the ore onto the table, means for dis- 45 charging the ore from the table, rabbles for rabbelling the ore on the table and for effecting movement of the ore from the place of charge to the place of discharge; a hood inclosing said table and rabbles, a 50 stack at the top of said hood to conduct the dust and gases away from said rabbles and to insure a circulation of air for progressively cooling the ore on the table during its movement from the place of charge to 55 the place of discharge; substantially as described.

2. In an apparatus for cooling hot ore or the like, the combination with two superposed flat cooling tables for supporting the ore in a 60 comparatively thin layer, means for charging the ore onto the upper table near the periphery thereof in a comparatively thin layer, means for discharging the ore from the upper table near the center thereof onto 65 the lower table, means for discharging the

ore from the lower table near the periphery thereof, and rabbles for rabbelling the ore and for effecting movement of the ore from the place of charge to the place of discharge of each table; of means for progressively 70 cooling the ore with air during its movement across each table from the place of charge to the place of discharge, the flow of air being in a direction opposed to that of the movement of ore; substantially as de- 75 scribed.

3. In apparatus for cooling hot ore or the like, the combination with a flat circular rotatable cooling table for supporting ore in a comparatively thin layer, means for rotating the table, means for charging the ore onto the table, means for discharging the ore from the table, and stationary rabbles for rabbelling the ore and for effecting movement of the ore from the place of charge to 80 the place of discharge; of means for spraying water immediately behind each rabbles for progressively cooling the ore on the table during its movement from the place of charge to the place of discharge; sub- 85 substantially as described.

4. In apparatus for cooling hot ore or the like, the combination with a circular table for supporting the ore, means for charging the ore onto the table near its center, means 90 for discharging the ore from the table near its periphery, and rabbles for rabbelling the ore and for effecting movement of the ore from the place of charge to the place of discharge; of means for conducting a circulat- 95 ing fluid cooling medium within the table from the periphery toward the center in such manner that heat from the ore is transferred to the fluid by conduction through the table; substantially as described. 100

5. In apparatus for cooling hot ore or the like, the combination with a rotatable hollow shaft, a circular supporting hollow table for the ore fastened to the shaft, means for charging the ore onto the table, means for discharging the ore from the table, and rabbles for rabbelling the ore and for effecting movement of the ore from the place of charge to the place of discharge; of conduits connecting the hollow interior of the table 110 with the hollow interior of the shaft and with a discharge outlet to conduct a current of fluid cooling medium therethrough for cooling the ore on the table substantially as described. 115

6. In apparatus for cooling hot ore or the like, the combination with a table for supporting ore, said table having air openings, means for charging the ore onto the table, means for discharging the ore from 125 the table, and rabbles for rabbelling the ore on the table and for effecting movement of the ore from the place of charge to the place of discharge; of a sprinkler for sprinkling liquid on the ore during its movement across 120 130

said table and means for circulating air through the openings in said table; substantially as described.

7. In apparatus for cooling hot ore or the like, the combination with a table for supporting the ore, means for charging the ore onto the table, means for discharging the ore from the table, and rabbles for rabbling the ore and for effecting movement of the ore from the place of charge to the place of discharge; of a plurality of narrow passages through the table for the purpose of inducing a current of air through the ore; substantially as described.

15 8. In apparatus for cooling hot ore or the like, the combination with a table for supporting the ore, means for charging the ore onto the table, means for discharging the ore from the table, and rabbles for rabbling

the ore and for effecting movement of the ore from the place of charge to the place of discharge; of means for conducting a circulating fluid cooling medium within the table in such manner that heat from the ore is transferred to the fluid by conduction through the table, and a plurality of radially arranged narrow passages passing through the table and closed to the cooling medium within the table for the purpose of inducing a current of air through the ore on the table; substantially as described.

In testimony whereof I affix my signature, in presence of two witnesses.
